C. L. GOODRUM

TELEPHONE EXCHANGE SYSTEM

Filed Oct. 25, 1920

Inventor:
Charles L. Goodrum.

by *W. Roberts* Atty

UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 25, 1920. Serial No. 419,214.

To all whom it may concern:

Be it known that I, CHARLES L. GOODRUM, a citizen of the United States, residing at New York, in the county of New York, 5 State of New York, have invented certain new and useful Improvements in Telephone-Exchange Systems, of which the following is a full, clear, concise, and exact description.

10 This invention relates to telephone exchange systems and more particularly to circuit arrangements for private branch exchanges, where such exchanges are to be used in connection with a main central office.

15 The object of the invention is to provide an improved circuit arrangement whereby a subscriber of the private branch exchange may at all times, selectively extend his line to an operator's position of the private branch exchange, or over an idle one of a plurality of trunks leading to the main central office.

20 In accordance with the present invention, the subscriber's line is provided with a non-numerical switch in addition to the usual line jack and line signal at the private branch exchange. In addition to the usual equipment for a common battery substation, the 25 subscriber's set is provided with a resistance in the line circuit, the resistance being normally short-circuited by means of a key. If the main central office is of the automatic type, the substation will also be equipped 30 with the usual impulse sender for the purpose of setting the switches at the main central office. Removal of the receiver from the switchhook causes the non-numerical switch to be actuated to extend the line over an idle one of a plurality of trunks leading to the central office, whereas actuation of the key and removal of the receiver from the switchhook causes the line signal at the operator's position to be actuated.

35 More specifically, each line is provided with a pair of line relays, one of which is marginal. Actuation of both of the line relays causes the operation of a magnet controlling the actuation of the non-numerical switch, and actuation of one of the line

relays causes the actuation of the line signal at the operator's position.

Referring to the drawing which shows only so much of a telephone exchange system as is necessary for a complete understanding of the invention, there is shown at A, a subscriber's station, connected to a jack 10 terminating at the operator's position, and having access to a non-numerical switch F, located at the private branch exchange. Associated with a plurality of line switches there may be a master switch schematically shown at M. The function of the master switch is to keep the contacts of the switch F in operative relationship with an idle trunk. The line and master switches may be of the general type described in U. S. Patent No. 1,203,166 to B. D. Willis of October 31, 1916. At O there is shown a portion of a line circuit, which may also terminate at the private branch exchange. At B there is shown a cord circuit for interconnecting lines of the private branch exchange. C represents schematically a portion of a connector circuit at the main central office connected by a trunk circuit having conductors 21 and 22 extending to the private branch exchange. D represents a portion of the line of a subscriber's station terminating in an automatic switch in the main central office.

25 The invention will be more readily understood from a detailed description of the operation of the system.

The party at station A desiring to extend his line over one of a plurality of trunks leading to the main central office, removes the receiver from the switchhook, which causes the operation of relays 5 and 6 over a path extending from battery, through the winding of relay 6, back contact and inner left-hand armature of relay 7, through the substation loop, outer left-hand armature and back contact of relay 7, and winding of relay 5 to ground. Relays 5 and 6 in operating, complete a circuit through the low resistance, right-hand winding of relay 7, thereby causing the attraction of the armature 70. Attraction of the armature 70 causes the closure of the contacts 27, 28 and 100

29 of the switch F in the well known manner thereby extending the line of the calling station through to the line relay 20 of the connector switch. For the purpose of simplicity, the line switch at the private branch exchange is shown connected directly to the connector C at the automatic exchange over a trunk line having the conductors 21 and 22. It will be understood, however, that the conductors 21 and 22 extending from the private branch exchange to the main central office may terminate in a non-numerical switch, or a selective switch of the automatic exchange. As soon as the switch at the private branch exchange is operated to extend the line of station A to the connector switch, relay 20 of the connector and relay 8 of the line switch are energized over a path extending from ground, right-hand winding of relay 20, conductor 22, contacts 28 of the line switch F, through to the winding of relay 8, through the substation loop, contacts 27 of the line switch F, conductor 21, and left-hand winding of relay 20 to grounded battery. Relay 8 thereupon attracts its armature and completes a circuit for slow-to-release relay 30. Relay 8 in operating also connects ground to the sleeve of jack 10 to render said jack busy. Relay 30, in operating, completes a circuit at its right-hand armature and front contact through the high resistance winding of relay 7. The left-hand armatures of relay 7 are then attracted, thereby disconnecting the line relays 5 and 6 from the calling line. Relays 5 and 6 are preferably of the slow-to-release type in order to insure the attraction of the armature or plunger 70 of the relay 7. Relay 30 in attracting its left-hand armature connects ground, through contacts 29 of the line switch F to contact 23 of the master switch, schematically indicated at M. The starting magnet 24 of the master switch is then operated and causes the master switch to advance the remaining plungers into operative relationship with the next idle trunk in the well known manner.

The subscriber at station A may now operate the sender S for the purpose of setting the connector switch upon the terminals of the desired line in the manner well known in the art. Relay 8 responds to each interruption in the line circuit, thereby momentarily opening the circuit for relay 30 during each interruption. Relay 30, however, being of the slow-to-release type, does not retract its armatures during the sending of a series of impulses. After the required number of impulses have been sent to set the brushes 40 and 41 upon the terminals 42 and 43 of the desired line, ringing current is automatically projected over the line leading to the desired substation D in the manner well-known in the art. When the subscriber at station D responds, ringing cur-

rent is automatically disconnected and the subscribers A and D are connected for conversation. The subscriber at substation A is supplied with talking current through the winding of relay 20 of the connector C 70 and the subscriber's station D is supplied with talking current through the windings of relay 50 of the connector C. Upon the completion of conversation and restoration of the receivers of the calling and called 75 subscribers to their respective switchhooks, all apparatus is restored to normal in the manner well known in the art.

It will next be assumed that the subscriber at station A desires connection with another 80 station of the private branch exchange. The subscriber at station A thereupon actuates the non-locking key 1 and removes the receiver 2 from the switchhook 3, thereby connecting the resistance 4 in the line circuit. 85 Relay 5 is of the marginal type and will not operate when the resistance 4 is connected in the line circuit. Relay 6 however will operate over a circuit extending from battery, winding of relay 6, back contact and 90 inner left-hand armature of relay 7, through the transmitter 55, switchhook 3, primary winding of induction coil 56, resistance 4, impulse sender S, outer left-hand armature and back contact of relay 7, and winding 95 of relay 5 to ground. Relay 6 in operating completes a circuit for relay 71 over a path extending from ground, armature and front contact of relay 6, armature and back contact of relay 5, and winding of relay 71 to 100 grounded battery. Relay 71 in operating completes a circuit at its inner left-hand armature and front contact for the lighting of line signal 12, and at its right-hand armature, locks up under control of slow-to-release relay 30. Relay 71 is preferably of the 105 slow-to-release type in order to insure its being locked up before line relay 6 retracts its armature. At the outer left-hand armature and front contact of relay 71, a circuit 110 is completed through the high resistance winding of relay 7, thereby causing said relay to attract its left-hand armatures, whereupon the line relays 5 and 6 are disconnected from the calling line. Relay 6 is also preferably 115 slow-to-release in order to insure the locking up of relay 71 before said relay 6 retracts its armature. The operator at the private branch noting the lighting of line signal 12, inserts the answering plug 11 120 of the cord circuit B into the jack 10, whereupon supervisory relay 60 of the cord circuit B is energized over a path extending from ground, lower left-hand winding of repeating coil 61, winding of relay 60, rings 125 of plug 11 and jack 10, through the substation loop, tips of jack 10 and plug 11 and upper left-hand winding of repeating coil 61 to battery. Supervisory lamp 62 is thereby 130 prevented from lighting. The operator then 135

- actuates a listening key (not shown) for the purpose of ascertaining the wants of the calling subscriber. Assuming that the subscriber of station O is desired, the operator 5 will insert the plug 14 of the cord circuit B into the jack 15 of the desired line and then actuate a ringing key (not shown) for the purpose of signaling the subscriber of station O.
- 10 Upon the response of the called subscriber, supervisory relay 16 of the cord circuit B will be actuated, thereby shunting the supervisory lamp 17 of the cord circuit B in the well-known manner. Upon completion 15 of conversation and restoration of the receivers to the switchhooks at the calling and called substations, supervisory lamps 62 and 17 will be lighted, indicating to the operator that conversation has been completed.
- 20 The operator noting these signals, removes the plugs 11 and 14 from their respective jacks, thereby restoring all apparatus to normal. The system is then ready for the next call.
- 25 It will be understood that the line circuit herein disclosed is equally well adaptable for use in connection with a manual main central office instead of an automatic main central office as shown. In such case, a line relay at the manual central office would be energized to display a signal before an operator, when the non-numerical switch F is actuated instead of the relay 20 of the connector switch C.
- 30 What is claimed is:
1. In a telephone exchange system, a subscriber's station, a key and a resistance thereat, a pair of line conductors extending from said station to an exchange, a line jack 40 and a line signal for said station at said exchange, a line switch for said station at said exchange, and means at said exchange controlled by said key and resistance over the pair of line conductors in series for selectively operating said line signal or said line switch.
  2. In a telephone exchange system, an exchange, a subscriber's line terminating therein, a plurality of line relays for said line, manual and automatic connective link circuits at said exchange for extending a call from said line, means including a resistance normally shunted by subscriber controlled means for selectively controlling the operation of said line relays over said line conductors in series to selectively extend the calling line to said manual or automatic connective terminals.
  3. In a telephone exchange system, a subscriber's station, a line circuit consisting of two conductors extending from said subscriber's station to a private branch exchange, a main central office, a plurality of trunk circuits extending from said exchange to said central office, a line switch at said exchange adapted upon actuation to extend said line circuit over an idle one of said trunk circuits to said central office, a line signal for said line at said exchange, a key and a resistance connected in said line circuit at the subscriber's station, said resistance being normally shunted by said key, and means dependent upon the actuation or non-actuation of said key when a calling party initiates a call for selectively operating the line signal or the line switch.
4. In a telephone exchange system, a two-conductor line circuit, a subscriber's station connected thereto having a switch hook and a non-locking key, a line signal, a line switch for said station having access to a plurality of trunks, and means controlled over the two conductors of said line circuit in series whereby upon the actuation of said key and switchhook said line signal is operated and upon the actuation of said switchhook alone said line switch is operated to extend the calling line to an idle trunk and to prevent the operation of said line signal.
5. In a telephone exchange system, a telephone line terminating in a jack at a first exchange, a station thereon, a line signal associated with said jack for said station, an automatic switch accessible to said station, a pair of line relays for said line, a second exchange, a trunk line extending from said first to said second exchange, a magnet for said switch adapted upon actuation to connect said telephone line to said trunk line, a circuit completed for said magnet when the pair of line relays are actuated, a circuit completed for said line signal when only one of said line relays is actuated, and manual switches at said exchange for causing said line circuit to selectively actuate one or both of said line relays.
6. In a telephone exchange system, a first exchange, subscribers' lines terminating therein, a second exchange, trunk lines extending between said exchanges, automatic switches at said first exchange, a line signal for each of said lines at said first exchange, and means under the control of a calling subscriber at said first exchange and operable over the two conductors of said line in series for selectively operating one of said automatic switches to extend said line to said second exchange or to operate the line signal of the calling line.
7. In a telephone exchange system, a first exchange, a subscriber's line terminating therein in a jack, a second exchange, a plurality of trunk lines extending from said first exchange to said second exchange, a line signal for said line associated with said jack, a line switch for said line adapted upon actuation to connect said calling line to an idle one of said trunk lines, a pair of line relays for said calling line, means op-

erable when both of said line relays are actuated to actuate said line switch, means operable when one of said line relays is actuated to actuate said line signal, and a switching device at the calling substation for determining the operation of said relays.

8. In a telephone system, a first exchange, a plurality of subscriber's lines terminating thereat, a plurality of non-numerical switches at said first exchange, a second exchange, a plurality of trunk lines extending from said first to said second exchange, a manually operable connecting circuit at said first exchange for interconnecting subscriber's lines, a key at each station of a line terminating at the first exchange, means operable in response to the removal of the receiver and actuation of the key at a station of a calling line for initiating a call at the first exchange, and means operable over the two conductors of said line in series in response to the removal of the receiver only for actuating one of said non-numerical switches to initiate a call over a trunk line extending to the second exchange.

9. In a telephone system, a central office, a subscriber's line terminating thereat, subscriber controlled means including a non-locking normally closed key, shunted by a resistance, in serial relation with said line, manual and automatic connecting link circuits at said central office for extending said line, and means at the central office con-

trolled by said key for selectively extending the calling line to said manual or said automatic link circuit.

10. In a telephone system, an exchange a subscriber's line terminating thereat, automatic and manual connecting link circuits at said exchange for extending a call from said line, a station for said line having a resistance, a key and a switch hook thereat, said resistance being normally short-circuited by said key, and a pair of relays at the central office, one of said relays operating when said switchhook is operated to extend the line to one of said connecting link circuits and both of said relays operating when said key and said switchhook are operated to extend the line to the other of said connecting circuits one of said relays being marginal and inoperative when said resistance is included in the line circuit.

11. In a telephone exchange system, a calling subscriber's station, a pair of line conductors extending from said station to an exchange, a manual connecting link circuit at said exchange, an automatic switch, and means controlled from said station over the pair of line conductors in series for selectively extending the calling station to said manual link circuit or to said automatic switch.

In witness whereof, I hereto subscribe my name this 19th day of October A. D. 1920.

CHARLES L. GOODRUM.

DISCLAIMER.

1,540,066.—*Charles L. Goodrum*, New York, N. Y. TELEPHONE-EXCHANGE SYSTEM.
Patent dated June 2, 1925. Disclaimer filed May 24, 1928, by the assignee,
Western Electric Company, Incorporated.

Hereby enters this disclaimer to the said claims of said Letters Patent which are in the following words to wit:

“2. In a telephone exchange system, an exchange, a subscriber's line terminating therein, a plurality of line relays for said line, manual and automatic connective link circuits at said exchange for extending a call from said line, means including a resistance normally shunted by subscriber controlled means for selectively controlling the operation of said line relays over said line conductors in series to selectively extend the calling line to said manual or automatic connective terminals.”

“6. In a telephone exchange system, a first exchange, subscriber's lines terminating therein, a second exchange, trunk lines extending between said exchanges, automatic switches at said first exchange, a line signal for each of said lines at said first exchange, and means under the control of a calling subscriber at said first exchange and operable over the two conductors of said line in series for selectively operating one of said automatic switches to extend said line to said second exchange or to operate the line signal of the calling line.”

“9. In a telephone system, a central office, a subscriber's line terminating thereat, subscriber controlled means including a nonlocking normally closed key, shunted by a resistance, in serial relation with said line, manual and automatic connecting link circuits at said central office for extending said line, and means at the central office controlled by said key for selectively extending the calling line to said manual or said automatic link circuit.

“10. In a telephone system, an exchange, a subscriber's line terminating thereat, automatic and manual connecting link circuits at said exchange for extending a call from said line, a station for said line having a resistance, a key and a switchhook thereat, said resistance being normally short-circuited by said key and a pair of relays at the central office, one of said relays operating when said switchhook is operated to extend the line to one of said connecting link circuits and both of said relays operating when said key and said switchhook are operated to extend the line to the other of said connecting circuits, one of said relays being marginal and inoperative when said resistance is included in the line circuit.

“11. In a telephone exchange system, a calling subscriber's station, a pair of line conductors extending from said station to an exchange, a manual connecting link circuit at said exchange, an automatic switch, and means controlled from said station over the pair of line conductors in series for selectively extending the calling station to said manual link circuit or to said automatic switch.”
